UNITED STATES PATENT OFFICE.

JOSEPH FIRMIN DIONNE AND JOSEPH ADOLPHE GUY, OF EDMUNDSTON,
CANADA.

RAIL AND TIE PLATE.

SPECIFICATION forming part of Letters Patent No. 617,234, dated January 3, 1899.

Application filed September 16, 1898. Serial No. 691,098. (No model.)

To all whom it may concern:

Be it known that we, JOSEPH FIRMIN DIONNE and JOSEPH ADOLPHE GUY, of Edmundston, in the Province of New Brunswick and Dominion of Canada, have invented a new and Improved Rail and Tie Plate, of which the following is a full, clear, and exact description.

Our invention relates to an improvement in rail and tie plates placed between the tie and the base of the rail; and the object of our invention is to lessen the wear of the tie by friction of the rail thereon, and also to prevent the spikes from coming up and permitting spreading of the rails from the true line of gage, and generally to resist the spreading of the rails, maintaining them at a true and perfect gage, and the invention also relates to a device to be used in connection with said plate for indicating the proper location of the rail-spikes.

Our invention comprises the novel features hereinafter described and claimed.

Figure 1 is a perspective view of our tie-plate. Figs. 2 and 3 are plans showing the plate in use, Fig. 2 showing the first position of the plate and Fig. 3 showing the final position of the plate. Fig. 4 is a cross-sectional elevation showing the plate in use.

The object of our invention is to provide a tie-plate which is cheap to manufacture and which will thoroughly hold the spikes in position, and thus maintain perfectly the gage of the rails. This plate is clearly shown in Fig. 1, and consists of a body A, which is flat and which when in use lies between the base of the rail and the tie. At each end of the plate is formed a flange D, the same being vertical in position, and the two flanges at opposite ends of the plate are at such a distance apart as to lie outside of the spikes when in use. These flanges strengthen the plate and furnish surfaces which may be struck by a hammer in forcing the plate into or out of position. At two diagonally-opposite corners of the plate are located offset portions B, which consist of strips having first an upward bend and then a horizontal

bend. These two offset portions are so located and are of such a size that when the plate is in position they partly cover the heads of the spikes F, by which the rail is held down.

In putting the plate in position the position of the spikes is first located on the tie and the spikes are partly driven. The plate is then placed between the rail E and the tie T in a diagonal position and between the spikes, as shown in Fig. 2, and the spikes F are then driven home. The plate is then turned by striking the flanges D at each end with a hammer, so as to place it square across the rail or in the position shown in Fig. 3. In this position the offset portions B cover the spike-heads and prevent them from working loose. The offset portions B and the flanges D offer a secure protection for the spike-heads and prevent the possibility of their working loose. The offset portions B and the flanges D should either be welded together or cast integral, so that each supports the other. The two other corners of the plate are provided with notches C so located that a spike could be driven into one or both of these to hold the plate in position. The plate is thus locked so that it cannot be removed without first drawing the locking-spikes.

Our tie-plate is constructed, preferably, of wrought or malleable iron or steel and may be cheaply stamped out. Its cost will therefore be very small, so that it may be widely used. Its use will tend to lengthen the life of the ties and also to hold the rails more securely upon the ties.

These plates may be made of all dimensions and materials to fit all styles and sizes of rails.

Having thus fully described our invention, we claim as new and desire to secure by Letters Patent—

1. A rail and tie plate, consisting of a flat body having portions at two diagonally opposite corners offset or bent upward to cover the spike-heads, said portions opening toward the sides of the plate and oppositely, and notches in the other corners of the plate adapt-

ed to receive locking-spikes, substantially as described.

2. A rail and tie plate, consisting of a flat body having portions at two diagonally opposite corners offset or bent upward to cover the spike-heads, said portions opening toward the sides of the plate and oppositely, and upturned flanges at the ends of the plate out-

side of the offset portions, substantially as described.

JOSEPH FIRMIN DIONNE.
JOSEPH ADOLPHE GUY.
